DETENTION WINDOW

William D. Bayley, Springfield, Ohio, assignor to
The William Bayley Company, Springfield,
Ohio, a corporation of Ohio

Application June 8, 1935, Serial No. 25,612

30 Claims. (Cl. 189—64)

This invention relates to window assemblies, and more particularly to window assemblies having transversely arranged bars dividing the window into spaces some of which are glazed, either with or without a group of spaces left vacant for ventilating area.

In conventional detention window assemblies as used until the last few years, guard bars were mounted exteriorly of the window assembly and independently thereof. There was no cooperation as to the structure between the guard bars and the window, the window assembly being entirely independent and separate from the guard bars. Recently another development has taken place wherein the guard bars have been removed in their entirety, the transversely arranged muntin bars of the window being spaced sufficiently close and made of sufficiently heavy material to prevent the escape or unauthorized entry of human bodies through the window. In the present embodiment the guard bars and the window have been united into a common structure, one reinforcing the other.

An object of this invention is to provide a dual-functional assembly wherein the parts are uniquely united and interlocked into a simple but convenient and efficient structure that is easily constructed with a small amount of labor at a small cost, without sacrificing efficiency and durability.

Another object of this invention is to provide a closure for a ventilating area of a window assembly that is easily assembled, that may be inserted on the job with a small amount of labor without sacrificing the efficiency or reliability.

Another object of this invention is to provide a window assembly wherein one group of muntin bars differs from another group of muntin bars, whereby one group is associated with the detention bars and the other group is offset with respect to the detention bars.

Another object of this invention is to provide a closure for the ventilating area with sufficient tolerance to permit insertion of the closure frame without extensive fitting operations and other expensive labor operations.

With the above primary and other incidental objects in view, as will more fully appear in the specification, the invention consists of the features of construction, the parts and combinations thereof, and the mode of operation, or their equivalents, as hereinafter described and set forth in the claims.

Referring to the drawings, Fig. 1 discloses a

perspective view of the window assembly as viewed from the inside.

Fig. 2 is a sectional view taken substantially on the line 2—2 of Fig. 1.

Fig. 3 is a sectional view taken substantially on the line 3—3 of Fig. 1.

Fig. 4 discloses a sectional view of a modification taken substantially on the line 4—4 of Fig. 5.

Fig. 5 discloses a horizontal sectional view taken substantially on the line 5—5 of Fig. 4.

Fig. 6 shows a sectional view of another modification taken substantially on the line 6—6 of Fig. 7.

Fig. 7 discloses a horizontal sectional view taken substantially on the line 1—7 of Fig. 6.

Fig. 8 shows another modification of a bar.

In the construction of window assemblies for penal institutions or where detention windows are required and in factories where ordinary windows are required, it is very desirable to have the window assembly made from parts that may be readily selected from stock and assembled on short notice so that the window assembly will not delay the work on the building. The location of the spaces left vacant for ventilating area may be selected and the closure frame inserted after the building has been completed. When this procedure is followed it is necessary either to require very accurate workmanship, the cost of which is prohibitive, or to provide a closure and the frame therefor which has sufficient tolerances to take care of irregularities in the window structure.

The closure assemblies disclosed herein are adapted for use where the tolerances are great but at the same time providing a window assembly that is neat, is water-tight, easily assembled, cheap, and at the same time efficient. The frame for the closure has been provided with projecting flanges which will cover irregularities, the space intermediate the flanges and the muntin bars bounding the ventilating area being concealed by putty or other suitable binding material or having the desired sealing qualities. The screen frames which oftentimes add to the clumsiness of the assembly are concealed in the present embodiment by being located intermediate the muntin bars bounding the ventilating area and the frame for the closure protecting the same. Likewise where detention bars are used it is desirable to incorporate the window structure in a unit including the detention bars. This may be accomplished by providing notches in the muntin bars in which the detention bars may be seated and

welded or otherwise secured. Instead of providing notches the transverse muntin bars may be provided with openings for the reception of the detention bars, the dimensions of the muntin bars running parallel to the detention bars being such as to permit alignment of the muntin bars with the detention bars. By so doing the massiveness of the assembly is greatly reduced.

Like parts are indicated by similar characters of reference throughout the several views.

Referring to the drawings the reference characters 10 indicate the vertical muntin bars and the reference characters 12 the horizontal muntin bars intersecting the vertical bars 10. The arrangement of these bars may be similar to that disclosed in the Bayley Patent No. 1,948,159 and the Zimmerman Patents Nos. 1,948,152 and 1,948,-153. The transversely arranged muntin bars 10 and 12 divide the window into a plurality of spaces 14, some of which are glazed leaving a group of spaces 16 vacant for ventilating area. If the window assembly is to be used for detention purposes, detention bars 18 and 20 extend across the ventilating area to protect the more vulnerable portion of the window assembly. The detention bars 18 and 20 may be aligned with or offset with respect to the muntin bars 10 and 12. The ventilating area 16 is provided with a closure 22 pivotally mounted at 24 to a frame 26.

By referring to Figs. 2 and 3 it may be seen that the closure 22 is provided with glazing 28 held in position by suitable metallic jambs 30 which may be removed if it is necessary to replace the glass. The frame 26 includes the horizontal top bar 32 substantially T-shaped, having an inwardly projecting flange 34, as best seen in Fig. 2. The vertical frame members 32 are identical to the top bar 32 in cross section. The sill 36 is hooked or laid over an upwardly projecting flange 38 of the muntin bar 40 bounding the ventilating area along the bottom thereof. The horizontal and vertical members 32 are provided with L-shaped stops 42 attached thereto by welding or riveting or in any other suitable manner. The vertical stops 42 have flanges 44 arranged in abutting relation with respect to the vertical muntin bars 10 bounding the ventilating area. Likewise the horizontal member 42 has its flange 44 abutting the horizontal muntin bar 12 bounding the ventilating area at the top.

In order to secure water-tightness, the joint between the bars 10 and the flanges 44 and the horizontal muntin bar 12 and the horizontal flange 44 are sealed by putty or suitable binding material or any other suitable sealing means, as shown by the reference character 46. It is to be noted that the stops 42 are medially placed with respect to the webs of the T-shaped members 32. This permits the insertion of the screen frame 50 in the pocket formed between the frame of the closure and the muntin bars bounding the ventilating area. This conceals the screen frame from the interior of the building and at the same time provides compactness, thereby diminishing the clumsiness of the window assembly.

Suitable inwardly projecting lugs 52 carried by the muntin bars 10 and 12 are provided with apertures receiving the bolts 54 holding the frame in a fixed relation with respect to the muntin bars, the screen 56 extending intermediate the lugs 52 and the frame 26 there being sufficient clearance between the flanges 34 and the lugs

52. The glazing in the fixed window spaces 14 is preferably located in the same plane as the glazing 28 so as to enhance the appearance of the window assembly. Instead of the lugs 52 being used, bolts 54 could either pass through or hook into the detention extending across the ventilating area.

In the modification disclosed in Figs. 4, 5, 6, and 7, the window assembly has been built around and incorporates the conventional detention bars 100. In the modification disclosed in Figs. 4 and 5 the horizontal muntin bars 102 provided with flanges 104 and 106 adjacent each end of the web 108, is provided with apertures for the reception of the detention bars 100. These bars are provided with a pair of flanges 110 and 112 cooperating to form a channel 114 for the reception of the glazing 116. With the exception of the muntin bars bounding the top of the window the glazing is seated in the channel 114 at the bottom that is filled with putty and located in the corner of the large channel underlying the web 108. Thus it may be readily seen that the glazing may be inserted from the inside of the window assembly and rotated into position in the space between the bars 100 and the normal position of the glazing 116.

To the flange 112 of the top muntin bar 108 is welded an extension 118 that provides a seat against which the glazing 116 abuts. This permits the insertion of the glazing from the inside of the window so that the window assembly may be glazed after the building has been completed.

If a space is left vacant for a ventilating area between two of the horizontal muntin bars, the ventilating area may not necessarily extend across the entire width of the window. The ventilating area is then preferably bounded by the vertical bars 130 which may be L-shaped and suitably welded or removably attached to member 131 having one edge welded to the detention bar 100. The glazing of the fixed spaces alongside the ventilating area may be held in position by a detachably mounted member 136 held in position by screws 138 engaging the flange 45 of the member 130. This assembly provides a fairly rigid frame bounding the ventilating area.

The closure 22 pivotally mounted in the frame 26 may be substantially identical in shape and design to the one disclosed in the modification shown in Figs. 1, 2, and 3, with the exception of the stops 42 being eliminated so that the flange of the T-shaped bar 32 abuts the flange 106 and the flange 130 bounding the ventilating area. The sill 36 in this modification is seated within member 140 provided with a dependent flange 142 mounted outside the flange 112. The frame of the closure is preferably held in position by bolts 144 engaging the lugs 146 welded to the muntin bars 108 and the L-shaped members 130. The bolts 144 pass through the frame of the screen 148 which is preferably L-shaped and projects into the pocket found between the frame of the closure and the bars bounding the ventilating area.

Referring to the modification disclosed in Figs. 6 and 7, the transverse horizontal muntin bars 150 are provided with arcuate notches 152 in which are seated the detention bars 100 and welded thereto. Instead of the glazing extending across the entire window assembly, as in Figs. 4 and 5, vertical muntin bars 154 which may be T-shaped in cross section, interlock the transverse muntin bars 150 but the T-shaped muntin bars 154 are of lesser dimension so as to per-

mit the alignment of the bars 154 with the detention bars 100.

In Fig. 8 the muntin bar 160 is similar to the above modifications excepting it is provided with 5 a channel 162 and another channel 164—one above and one below the web for the reception of the window panes—not shown.

From the above description it will be apparent 10 that there is thus provided a device of the character described possessing the particular features of advantage before enumerated as desirable, but which obviously is susceptible of modification in its form, proportions, detail construction and arrangement of parts without departing 15 from the principle involved or sacrificing any of its advantages.

While in order to comply with the statute, the invention has been described in language more or less specific as to structural features, it is to 20 be understood that the invention is not limited to the specific features shown, but that the means and construction herein disclosed comprise the preferred form of several modes of putting the invention into effect, and the invention is therefore claimed in any of its forms or modifications 25 within the legitimate and valid scope of the appended claims.

Having thus described my invention, I claim:

1. A window assembly including muntin bars 30 having a web, a pair of flanges projecting from one side thereof providing a channel like seat for glazing, and at least one flange upon the opposite side of the web in aligned relation with respect to one of said pair of flanges for supporting the glazing, said flange upon said opposite side being longer than one of the flanges of said pair.

2. A window assembly including a plurality of 40 parallel muntin bars dividing the window into a plurality of spaces, at least some of which are glazed, each of said muntin bars having a web, a pair of flanges projecting from one side of the web forming a glazing channel in which the glazing is seated one of said flanges being medially positioned with respect to the web, and a flange 45 projecting from the opposite side of the web forming an abutment for the glazing, said last mentioned flange being arranged in aligned relation with respect to one of said first mentioned flanges.

3. A window assembly including a plurality of 50 parallel muntin bars dividing the window into a plurality of spaces, at least some of which are glazed, each of said muntin bars having a web, a pair of flanges projecting from one side of the web forming a glazing channel in which the glazing is seated at least one of said flanges being medially positioned with respect to the web, and a pair of flanges on the opposite side of the web 55 arranged in spaced relation and adjacent the ends of the web.

4. A window assembly including a plurality of 60 parallel muntin bars dividing the window into a plurality of spaces, at least some of which are glazed, each of said muntin bars having a web, plus a pair of flanges projecting from opposite 65 ends of the web, against one of which the glazing is seated, and a pair of flanges projecting from the opposite side of the web, one of which is medially placed with respect to the web and cooperating with the other flange of the second pair to form a glazing channel.

5. A detention window assembly including a 70 plurality of parallel muntin bars, a plurality of 75 transversely arranged muntin bars of lesser width

than said first mentioned muntin bars intersecting the same to divide the window into a plurality of glazed spaces, and detention bars supported by the first mentioned bars and arranged in aligned relation with respect to the bars of lesser 5 width to be concealed thereby.

6. A detention window assembly including a 10 plurality of parallel muntin bars dividing the window into a plurality of spaces some of which are glazed leaving at least one space vacant for ventilation, detention bars intersecting said muntin bars offset with respect to said glazing, transverse angle bars extending across the ends of the ventilating area and supported by the muntin bars bounding the same, said angle bars being 15 aligned with detention bars, and means for connecting the angle bars to the aligned detention bars to reinforce the bars bounding the ventilating area.

7. A detention window assembly including a 20 plurality of parallel muntin bars dividing the window into a plurality of spaces some of which are glazed leaving at least one space vacant for ventilation, detention bars intersecting said muntin bars offset with respect to said glazing, a 25 pair of angle bars spanning the muntin bars bounding the ventilating area and cooperating therewith to enclose the ventilating area, a closure mounted in the ventilating area and including a fixed frame supported by said enclosing 30 bars, the fixed frame being arranged to form a channel intermediate said enclosing bars and said frame and a screen assembly extending across the ventilating area having the frame thereof seated in said channel. 35

8. A detention window assembly including a 40 plurality of parallel muntin bars dividing the window into a plurality of spaces some of which are glazed leaving at least one space vacant for ventilation, detention bars intersecting said muntin bars offset with respect to said glazing, a pair 45 of angle bars spanning the muntin bars bounding the ventilating area and cooperating to enclose the same and a second pair of angle bars each having one flange attached to a corresponding flange of one of said first mentioned bars, the other flanges of said bars cooperating to form glazing channels.

9. A detention window assembly including a 50 plurality of parallel muntin bars dividing the window into a plurality of spaces some of which are glazed leaving at least one space vacant for ventilation, detention bars intersecting said muntin bars offset with respect to said glazing, a pair 55 of angle bars spanning the muntin bars bounding the ventilating area and cooperating to enclose the same and a second pair of angle bars each having one flange attached to a corresponding flange of one of said first mentioned bars, the other flanges of said bars cooperating to form 60 glazing channels, a closure for the ventilating area having a flange supported by the bars bounding said area and a screen mounted across the ventilating area having an L-shaped cross sectional frame having a flange aligned with one of 65 the flanges of the angle bars bounding the ventilating area.

10. A detention window assembly including a 70 plurality of muntin bars dividing the window into a plurality of spaces some of which are glazed 75 leaving at least one space vacant for ventilating area bounded by muntin bars, a closure for the ventilating area and including a frame extending into the ventilating area, lugs projecting from bars bounding the ventilating area, means for 80 85 90 95 98 - securing said frame to said lugs and pliable means mounted intermediate the frame and the bars bounding the area for sealing the frame in the closure to provide water tightness.
5. 11. A window assembly including a plurality of muntin bars dividing the window into a plurality of spaces some of which are glazed leaving at least one space vacant for ventilating area bounded by muntin bars, said muntin bars having 10 flanges adjacent one edge of the web thereof, and a closure for the ventilating area, said closure unit including a frame projecting partially into the ventilating area, and a movable closure mounted in the frame and including flanged 15 muntin bars having the webs directed in the opposite direction of the webs of the first mentioned muntin bars whereby the glazing abutting the flanges of the fixed area is substantially coplanar to the glazing abutting the flange of the closure.
20. 12. A detention window assembly including a plurality of parallel muntin bars dividing the window into a plurality of spaces some of which are glazed leaving at least one space vacant for ventilation, detention bars intersecting said 25 muntin bars offset with respect to said glazing, a closure for the ventilating area including a frame spaced from but in close proximity to the detention bars extending across the ventilating area, and a screen extending across the ventilating 30 area mounted intermediate the closure and the detention bars, the thickness of the frame of the screen exceeding the distance between the closure and the detention bars.
35. 13. A detention window assembly including a plurality of parallel muntin bars dividing the window into a plurality of spaces at least some of which are glazed, a plurality of transversely arranged detention bars intersecting the muntin bars, said detention bars differing in shape from 40 the shape of the muntin bars, said muntin bars having a pair of flanges offset with respect to said detention bars for supporting the glazing in a plane offset with respect to said detention bars.
45. 14. A detention window assembly including a plurality of parallel muntin bars dividing the window into a plurality of spaces at least some of which are glazed, detention bars transversely arranged with respect to said muntin bars, the detention bars being partially offset with respect to 50 the muntin bars, said muntin bars having a pair of flanges spaced with respect to the detention bars forming channels for the glazing extending in a plane offset with respect to the detention bars.
55. 15. A detention window assembly including a plurality of muntin bars dividing the window into a plurality of spaces some of which are glazed leaving at least one space vacant for ventilation, transversely arranged detention bars extending 60 across the ventilating area arranged in a plane offset with respect to the plane of the glazing, a closure for the ventilating area offset from but in close proximity to the detention bars, a screen for the ventilating area mounted intermediate the closure and the detention bars, said screen including a frame having an L-shaped cross sectional area, and a bolt passing through the screen frame for retaining the closure in position.
70. 16. A detention window assembly including a plurality of parallel muntin bars dividing the window into a plurality of spaces some of which are glazed leaving at least one space vacant for ventilation, each of said muntin bars including a web 75 terminating in integral flanges, a portion of the web being angularly disposed with respect to the remainder thereof, detention bars transversely arranged with respect to said muntin bars offset with respect to the glazing, said detention bars being united to the muntin bars so as to form a 5 unitary structure.
17. In a detention window assembly a plurality of parallel muntin bars dividing the window into a plurality of spaces at least some of which are glazed, said muntin bars including a web having 10 integral flanges adjacent thereto, and a plurality of transversely arranged detention bars intersecting the webs between said flanges, said detention bars being offset with respect to the glazing. 15
18. A detention window assembly including a plurality of parallel muntin bars dividing the window into a plurality of spaces some of which are glazed, leaving at least one space vacant for ventilation, detention bars mounted in fixed relation with respect to said muntin bars and offset with respect to said glazing, a pair of members spanning the muntin bars bounding the ventilating area and cooperating therewith to enclose the ventilating area, a closure mounted in the ventilating area and including a fixed frame supported by said members, the fixed frame being arranged to form a channel intermediate said members and said frame and a screen assembly extending across the ventilating area having the 25 frame thereof seated in said channel. 30
19. A detention window assembly including a plurality of parallel muntin bars dividing the window into a plurality of spaces, some of which are glazed, leaving at least one space vacant for ventilation, detention bars mounted in fixed relation with respect to said muntin bars and offset with respect to said glazing, a pair of members spanning the muntin bars bounding the ventilating area and cooperating therewith to enclose the ventilating area, and a closure mounted in the ventilating area for closing the same, the glass of the fixed portion and the closure for the ventilator portion intervening between the inmates and the detention bars. 40 45
20. A detention window assembly including a plurality of parallel muntin bars dividing the window into a plurality of spaces some of which are glazed, leaving at least one space vacant for ventilation, transversely arranged detention bars mounted in fixed relation with respect to said muntin bars offset with respect to said glazing, a pair of bars spanning the muntin bars bounding the ventilating area and cooperating to enclose the same and a second pair of bars each having one edge attached to a corresponding edge of one of said first mentioned bars, the other edges of said bars forming glazing supports. 50 55
21. A detention window assembly including a plurality of parallel muntin bars dividing the window into a plurality of spaces some of which are glazed, leaving at least one space vacant for ventilation, detention bars mounted in fixed relation with respect to said muntin bars offset with respect to said glazing, a pair of bars spanning the muntin bars bounding the ventilating area and cooperating to enclose the same and a second pair of bars each having one edge attached to a corresponding edge of one of said first mentioned bars, the other edges of said bars cooperating to form glazing channels, a closure for the ventilating area having a flange supported by the bars bounding said area and a screen 60 65 70 75 80

- mounted across the ventilating area having a frame aligned with one of the flanges of the bars bounding the ventilating area.
22. A detention window assembly including a plurality of muntin bars dividing the window into a plurality of spaces some of which are glazed, leaving at least one space vacant for ventilating area bounded by muntin bars, a closure for the ventilating area and including a frame extending into the ventilating area, means for securing said frame to said muntin bars and pliable means mounted intermediate the frame and the bars bounding the area for sealing the frame in the closure to provide water tightness.
23. A detention window assembly including a plurality of muntin bars dividing the window into a plurality of spaces some of which are glazed, leaving at least one space vacant for ventilating area bounded by muntin bars, a closure for the ventilating area and including a frame extending into the ventilating area, means for securing said frame to said muntin bars, said frame and said muntin bars forming pockets, and pliable means mounted in the pockets formed by the frame and the bars for sealing the frame to provide water tightness.
24. A window assembly including a plurality of muntin bars dividing the window into a plurality of spaces some of which are glazed leaving at least one space vacant for ventilating area bounded by muntin bars, said muntin bars having flanges adjacent one edge of the web thereof, and a closure for the ventilating area, said closure unit including a frame adjacent to the ventilating area, and a movable closure mounted in the frame and including flanged muntin bars having the webs directed in the opposite direction of the webs of the first mentioned muntin bars.
25. A detention window assembly including a plurality of parallel muntin bars dividing the window into a plurality of spaces some of which are glazed, leaving at least one space vacant for ventilation, detention bars mounted in fixed relation to said muntin bars offset with respect to said glazing, a closure for the ventilating area including a frame spaced from but in close proximity to the detention bars extending across the ventilating area, and a screen extending across the ventilating area mounted intermediate the closure and the detention bars, the thickness of the frame of the screen exceeding the distance between the closure and the detention bars.
26. A detention window assembly including a plurality of muntin bars dividing the window into a plurality of spaces some of which are glazed, leaving at least one space vacant for ventilation, transversely arranged detention bars extending across the ventilating area arranged in a plane offset with respect to the plane of the glazing, a closure for the ventilating area offset from but in close proximity to the detention bars, a screen for the ventilating area mounted intermediate the closure and the detention bars, said screen including a frame having an L-shaped cross sectional area, and means for retaining the screen in position.
27. A detention window assembly including a plurality of parallel muntin bars dividing the window into a plurality of spaces some of which are glazed, leaving at least one space vacant for ventilation, said muntin bars terminating in flanges on the inner side of the window, the glazing abutting said flanges and held in position by putty inaccessible from the interior of the window assembly, a closure for the ventilating area including a frame mounted on the muntins bounding the ventilating area, and a closure movably mounted in said frame, said closure including a frame supporting the glazing held in position by putty accessible from the inside of the window and retaining members carried by said movable frame for preventing the removal of the glazing in the absence of putty.
28. A detention window assembly including a plurality of parallel muntin bars dividing the window into a plurality of spaces some of which are glazed leaving an unglazed ventilating area bounded by muntin bars, putty holding the glazing in position, said putty being inaccessible from the inside of the window to prevent tampering by inmates, a movably mounted closure for the ventilating area, said closure including glazing held in position by putty accessible from the inside, and auxiliary means limiting the movement of the glazing in the closure in the absence of putty.
29. A window assembly including a frame surrounding a ventilating area, a closure for the ventilating area including a frame mounted contiguous to the first frame, means for securing said frames together, and initially plastic means mounted intermediate the frames for sealing the juncture between the frames to secure water tightness.
30. A window assembly including a plurality of muntin bars dividing the window into a plurality of spaces some of which are glazed, leaving at least one space vacant for ventilating area bounded by muntin bars, said muntin bars having flanges adjacent the edge of the web thereof, the glazing abutting said flanges, and a closure for the ventilating area, said closure unit including a frame projecting into the opening of the ventilating area, and a movable closure mounted in the frame and including flanged members having the webs thereof directed in the opposite direction of the webs of the muntin bars so that the glazing of the closure is coplanar with the glazing of the fixed spaces.
